UNITED STATES PATENT OFFICE.

EDWARD LIVERMORE, OF NEW-YORK, N. Y., ASSIGNOR TO HORACE GALPEN, OF SAME PLACE.

FURNACE FOR CONSUMING SMOKE AND HEATING WATER.

SPECIFICATION forming part of Letters Patent No. 274,450, dated March 20, 1883.

Application filed August 11, 1882. (No model.)

To all whom it may concern:

Be it known that I, EDWARD LIVERMORE, of New York, in the county of New York and State of New York, have invented certain new and useful Improvements in Furnaces for Consuming Smoke and Heating Water; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to improvements in steam-boiler and other furnaces, but has reference more especially to the furnaces of stationary boilers for evaporating purposes, heating or roasting ores, and other manufacturing purposes.

The objects of the invention are to accelerate to the greatest possible extent the generation of steam, to diminish the consumption of fuel in proportion to the quantity of water evaporated, and to more effectually consume the smoke and waste gases.

In rapidly-burning combustion-chambers carbureted gas is rapidly developed; but unless it is rapidly utilized by combining it with oxygen a portion is entirely lost. Greater rapidity of combustion has consequently heretofore been attended with a great loss of fuel passing off as waste gases, and such is the case when this accelerated combustion is obtained by means of chimney-draft alone.

I am aware that artificial draft provided by fans, steam-jet blowers, and other means has been employed with more or less advantage to accelerate combustion; but when the blast is discharged underneath the grates of furnaces (the usual mode) it involves the rapid destruction of the fire-bars. The objects to be gained, therefore, are the greatest possible rapidity in the decomposition of the fuel, and at the same time to give such an amount of oxygen, and so distributed, as shall be best calculated to insure its perfect combination with the carbureted gases given off in process of decomposition of the fuel, in order that perfect combustion of the fuel is effected. This result is attained by means of my invention.

To this end my invention consists in the employment of an artificial blast introduced through conduits located in the side walls of

the furnace, and running transversely across the furnace in conduits protected by fire-clay or other refractory material, held in place by transverse and vertical water pipes or tubes.

It further consists in conveying a blast of air to the fire through hollow grate-bars, and thence through an air-conduit in the bridge-wall, by which the air is thrown into a contracted throat at such point, and in combination with the combined steam and hot-air blast coming through the before-described conduits and emitted from the side of the throat, by which the combined blasts are more intimately mixed for the more perfect combustion of all the gases. I also convey a portion of the blast to the entrance of the flue immediately in front of the suspended bridge over the incandescent fuel by jets from a perforated pipe running transversely through the pendent partition or bridge, which is elevated above the fire in order that the blast shall be distributed so as to insure the complete admixture of the gases for effecting nearly complete combustion. To supply the rear combustion-chamber back of the bridge-wall with air I make perforations in the bridge-wall under the grate. It will be observed that the air, before it reaches the point of contact with the carbureted and liberated gases, acquires a high degree of heat.

For the better understanding of my invention, and to more perfectly illustrate the same, I will proceed to describe the accompanying drawings, in which—

Figure 1 illustrates a side view of my improved boiler-setting, it being partly in section and partly in elevation. Fig. 2 shows a horizontal section through the heating and pipe-protecting wall, and through one of the heating-pipes a plan view of the transverse wall. Fig. 3 shows a vertical cross-section through the transverse wall, clearly illustrating the construction and arrangement of the vertical and transverse water-pipes which hold the wall or fire-brick material from disintegrating. This figure also shows the air-heating pipes running across the wall and their controlling-damper. Fig. 4 shows a like construction and arrangement of air and steam heating conduits, transverse suspended partition, and delivery-jets as that shown by Fig. 1, Sheet 1, but without the nest of water-sustaining walls. Fig. 5 shows a horizontal section taken on a line through the furnace of Fig.

4. Fig. 6 shows the contour of the side pipes when located in the side and cross walls. Fig. 7 shows a perspective view of the steam-supply pipe and register, with elongated holes to enable the register to slide over the steam-pipe.

The same letters denote like parts in all the figures.

A is the boiler; B, the furnace; C, the inner side walls inclosing air and steam pipes; D, 10 hollow grate-bars; E E, water-cylinders running transversely across the furnace, their ends resting in the side walls thereof. These water-cylinders E play an important part in the construction of my furnace, as they support the series of vertical water-tubes, and also 15 the transverse wall which incloses the hot-air and steam pipes, as well as the means of circulation, and through which the boiler is to be blown off.

20 F is the circulating-pipe, connecting to the blow-off G at one end and to the steam-delivery pipe at the other end.

G is the sediment blow-off pipe, perforated its entire length, so that the sedimentary 25 deposits are blown from all parts of the bottom of the boiler.

H is the outside connecting-pipe, and I steam-delivery pipe, perforated on its lower side. The object of perforating the steam-pipe in this way is to separate the steam from 30 the water. The steam generated in the water-cylinders of course is what may be termed "wet" or "saturated" steam, and when thrown downwardly, as shown, the steam, being 35 lighter, ascends, while the water by its specific gravity falls, and thus the separation is complete. I also place the end of the delivery-pipe as far from the steam-dome as possible, so that 40 all the water will be separated from the steam before it reaches the dome.

J J are air-heating pipes running circuitously back and forward through the transverse partition-wall and terminating in nozzles facing toward the furnace-door. I find it important 45 to supply the half-burning mass of fuel in the front chamber with highly-heated air. The air and gases readily unite at certain temperatures, and are in this mixed state carried under the partition into the throat, where they are 50 met by other series of mixed highly-heated air and steam jets. The flame at this point—viz., the narrowed throat—is so intensely hot that all the mixture of carbureted gases, highly-heated air, and superheated steam is completely 55 consumed, so that no smoke is formed, and thereby avoided.

C and K represent a series of steam and air pipes embedded in brick-clay or other refractory material, and are partly supported by 60 the water-pipes F F, and partly by a projection running along the side walls of the furnace. These pipes are shown detached by Fig. 6. They run along the inside of the walls, and then turn across the bridge-wall to the opposite 65 sides of the furnace, where they deliver jets of air and steam opposite each other, and thus while the gases are passing through the throat

they are met by these mingling gases, ignited, and entirely consumed.

L is the throat of the furnace, formed by the 70 bridge-wall, the side-perforated walls, and the transverse wall, and arranged in such manner that all the gases are compelled to pass through it and through a shower of jets of combustible gases, wherein they are consumed. 75

M M are the side arch walls for the support of the air and steam pipes and their covering. This covering is simply mortar, or some fire-proof plastic material which will withstand intense heat. The object of the wall is to protect the air and steam supply pipes from the intense heat of the fire, and at the same time transmit sufficient heat to highly heat the air and superheat the steam. The pipes and side walls are held firmly in place by tie-bolts, as 85 shown.

N is the rear combustion-chamber, and is supplied with atmospheric air through the bridge-wall at f; but, as a general thing, combustion is complete when the heat reaches the 90 chamber N.

P is the transverse hanging wall; or it may be supported on water-pipes or other suitable means. This wall or partition is formed between two sets of water-pipes in the following 95 manner: After the water-pipes are in position air and steam pipes are then run across at right angles to the water-pipes. Fire-clay mortar is then filled in between the pipes, which completely covers and protects them from the 100 intense heat of the fire. In Fig. 4 the transverse wall is supported by the air-pipes and the side wall of the furnace, as well as with the water-circulating pipes. It will be observed that the grate-bars are hollow, and that an 105 additional supply of hot air is supplied through them, passing through a conduit in the bridge-wall, and then supplied at the throat of the furnace. In this way the fuel is supplied with hot air from the sides, from the front, and from 110 under the throat in regulated quantities, which assures complete combustion of the fuel-gases, in which smoke may specially be included.

In using a steam-jet blast advantageously for creating the required amount of air-blast 115 I apply one steam-blower for every two adjacent air-pipes. The number of dischargers to be placed in one furnace of a steam-boiler will necessarily depend on the power and size of the boiler required. The object is to produce 120 many points of direct contact, so as to procure a better commingling for incandescence and complete union of the elements of combustion. Thus we have superheated steam and hot air injected simultaneously into the throat out of 125 each side or jacket of the duplex ejectors, mixing the elements of combustion, thus causing the more complete combustion of the smoke and all the gases.

Circulation of the water and clean boiler-sheets are two important factors in the generation of steam. If the water is sluggish in its circulation, good results will not follow, as circulation is necessary to carry the heat from

the generating surfaces to the portions of the boiler that are not so hot. If the boiler-plate is covered with precipitate or sedimentary deposit, the transmission of heat through the 5 plate must be very slow, as is well known to engineers. To provide good circulation and clean boiler-sheets are notable objects of my invention.

Having described my invention and the 10 means of utilizing and operating the same, what I claim as new, and desire to secure by Letters Patent, is—

1. The combination, in a furnace for consuming smoke and waste gases, of a series 15 of influent air and steam pipes extending around in front of the bridge-wall to the opposite side of the furnace and terminating at the partition-wall P, said pipes being embedded in fire-proof material and perforated, and arranged to throw mingled jets of heated steam and air from each side of the furnace and in violent contact with each other within the throat L, for the better admixture and consumption of the gases, substantially as de- 25 scribed.

2. In a steam-generator, the combination, 30 with the boiler, of a series of vessels connected together, and having water-tubes ascending therefrom and communicating with the water- space of the boiler, said ascending tubes being arranged in such manner as to form a space between them for a fire-wall, the said tubes and vessels being arranged across the furnace, forming a partition near the throat thereof, 35 substantially as described.

3. An improvement in boiler-furnaces for 40 burning smoke and generating steam, consisting of the tubular side walls having alternate steam and air pipes extending around and in front of the bridge-wall, and a transverse partition composed of water-pipes and refractory materials, said parts forming a contracted throat, the partition being provided with trans- 45 verse air-pipes for heating and feeding air to the furnace in front of the partition, substan- tially as described.

4. The combination, in a boiler-furnace, of 50 the tubular side walls, for heating air and superheating steam, with the transverse partition constructed as described, and with the water supporting and circulating pipes so ar- 55 ranged as to partially support the tubular walls and cause circulation through the parti- tion-pipes, substantially as shown.

5. The combination, with a furnace for con- 60 suming smoke and generating steam, of the transverse partition located in fire-box, constructed of water-pipes, air-pipes, and refractory material, said partition being arranged to be partially supported by the side walls of 65 the furnace and the water-circulating pipes, as described.

6. The combination, in a furnace for steam- 70 boilers and for supplying air thereto, of the side air and steam pipes arranged and perforated as described, the hollow grate-bars com- 75 municating with the throat of the furnace

through the bridge-wall, and the cross air- 70 pipes in the partition, all arranged for the more perfect combustion of fuel, substantially as de- 75 scribed.

7. The combination, in steam-boiler furnaces, of the side fire-walls, partially supported by brackets (see Fig. 3) and partly by wa- 75 ter-pipes F, with the transverse partition ar- ranged between the water pipes or tubes, and with the vessels or cylinders E, adapted to support said partition, for the purpose set forth.

8. In a steam-boiler furnace, the combina- 80 tion of the transverse pipes and short vertical pipes, the bottom set in rows and adapted to hold a fire-wall between them, the upper se- 85 ries of transverse pipes having ascending tubes connected to the water-space of the boiler, and the lower series or cylinders hav- ing connections with the bottom and top wa- 90 ter-space of the boiler for the reception of wa- ter and discharge of steam, substantially as described.

9. The combination, in a boiler-furnace, of 95 the side tubular walls, the rear tubular wall, and the bridge-wall extending to near the wa- 90 ter-line of the boiler, with the partition-wall supported as described, said walls being pro- 95 vided with steam and air heating tubes, sub- stantially as described.

10. The combination, in a steam-boiler fur- 100 nace, of the side heating tubular walls, hav- ing alternate steam and air heating pipes, 105 with the transverse partition-wall, also hav- ing steam and air heating pipes, each of said walls being provided with independent regis- 110 ters for controlling the supply of air and steam passing through them, the ends of said side walls and the partition-wall being arranged to form a narrowed throat, substantially as described, for the purpose of consuming the 115 gases passing through said throat.

11. The combination, with the furnace of a 110 steam-boiler, of the transverse water-cylinders, the vertical pipes connecting the same, the as- 115 cending pipes connecting the said cylinders to the boiler, the longitudinal pipes F, and the inner pipes, G and I, perforated as described, 120 and operating as and for the purpose set forth.

12. The combination, in a steam-boiler fur- 120 nace having tubular side fire-walls, of ex- 125 ternal registers for controlling the supply of air to the tubes therein, the walls also having steam-tubes for supplying superheated steam to the throat of the furnace, and steam-nozzle for supplying said tubes, the sliding covers of 130 said registers being provided with elongated holes, for allowing the reciprocating move- 135 ments of the slide without interfering with the steam-nozzles passing through them, in the manner set forth.

In testimony that I claim the foregoing as my own I affix my signature in presence of two 130 witnesses.

Witnesses: EDWARD LIVERMORE.
AUGUSTUS DAVIS,
M. P. CALLAN.
